UNITED STATES PATENT OFFICE.

TRAUGOTT GOLDE, OF GERA, GERMANY.

VEHICLE-HOOD.

1,034,900.

Specification of Letters Patent.

Patented Aug. 6, 1912.

Application filed August 3, 1911. Serial No. 642,120.

To all whom it may concern:

Be it known that I, TRAUGOTT GOLDE, a subject of the Prince of Reuss, Younger Line, residing at Gera, Reuss, Germany, 5 have invented a new and Improved Vehicle-Hood, of which the following is a specification.

This invention relates to a foldable hood for automobiles and other vehicles which 10 is firmly braced from end to end in a superior manner, so that it is not liable to vibrate during travel or by wind-action.

In the accompanying drawing: Figure 15 1 is a side elevation of a vehicle hood embodying my invention showing it open, and Fig. 2 is a similar view showing it folded.

To the back of the car body are pivoted a pair of rear bows *o* and *b* turning on a common center *a* and adapted to diverge 20 from the bottom toward the top when unfolded. To rearmost bow *o* there is pivoted at *o'* the rear member *d* of an articulated brace, the front member *e* of which is pivoted to the foremost bow *b* at *b'*, the pivots *o' b'* being equidistant from pivot *a*. The 25 joint of the articulated brace is formed intermediate bows *o, b* and is equidistant from pivots *o' b'*. Intermediate bows *o, b* there is interposed a third bow *w* which is connected to bows *o, b* by toggles *v*. Front 30 brace member *e* extends a distance beyond bow *b* and to its forward end there is pivoted at *f'* the rear end of a link *f* to the forward end of which the outrigger bow *x*

is pivoted at *x'*. A foldable arm *y* pivoted 35 to the link *f* at *f'* extends downwardly and rearwardly to bow *b* to which it is pivoted at *y'*. To link *f* is further pivoted at *z'* a supplemental bow *z* so as to be located intermediate the outrigger bow *x* and arm *y*. 40 It will be seen that arm *y* efficiently braces the link *f* which supports the outrigger bow as well as the supplemental bow. During the folding operation of the top, joint *f'* will break upwardly, while joint *x'* will 45 break downwardly, which movement will be readily followed by arm *y*, so that the parts will become tightly packed against each other.

I claim:

A vehicle hood comprising a pair of rear bows, an articulated brace pivoted to said bows and having a joint intermediate the bows, the brace member extending a distance in front of the foremost bow, a link 55 pivoted to the projecting end of said brace member, an arm extending downwardly from the link and pivoted to said link and to the foremost bow, an outrigger bow pivoted to the forward end of the link, and a 60 supplemental bow pivoted to the link intermediate the outrigger bow and the arm.

In testimony whereof I affix my signature in the presence of two witnesses.

TRAUGOTT GOLDE.
